DOUBLE STUDY CARRELL UNIT

John L. Gianfagna, 102 Crestwood Circle,
Marietta, Ohio 45750

Original design application June 4, 1968, Ser. No. 12,554.
Divided and this application May 14, 1969, Ser. No.
18,669

Term of patent 14 years

Int. Cl. D6—01

U.S. Cl. D33—11

FIG. 1.

FIG. 2.

FIG. 1 is a front perspective view of a double study carrell unit showing my new design; and

FIG. 2 is a front view thereof.

The end of the unit not shown is like the end shown in FIG. 1 while the rear is the same in appearance as the front thereof.

This application is a division of design application No. D. 12,554, filed June 4, 1968.

I claim:

The ornamental design for a double study carrell unit, substantially as shown and described.
